UNITED STATES PATENT OFFICE.

ROBERT DRUMMOND, OF PHILADELPHIA, PENNSYLVANIA.

PERMUTATION-PADLOCK.

1,081,218.

Specification of Letters Patent.

Patented Dec. 9, 1913.

Application filed March 30, 1912. Serial No. 687,367.

To all whom it may concern:

Be it known that I, ROBERT DRUMMOND, a citizen of the United States of America, residing at Philadelphia, in the county of Philadelphia and State of Pennsylvania, have invented certain new and useful Improvements in Permutation - Padlocks, of which the following is a specification.

My invention relates to locks and more particularly to the type of lock known as permutation padlocks.

The object of my invention is to provide a lock comprised of but few parts compactly arranged within a comparatively small casting or shell.

the accompanying drawings Figure 1 is a side elevation of my improvement. Fig. 2 is a vertical section through Fig. 1. Fig. 3 is a section on the line 1—1 Fig. 1. Fig. 20 4 is a plan view of one of the tumblers and Fig. 5 is a view of spindle detached.

Referring more particularly to the drawings, 1 designates a casing or shell of any convenient shape formed from a single piece 25 of any suitable material, but preferably of non-corrosive metal. One end of the casing is formed with a cylindrical enlargement 2 bored to form a cylindrical tumbler chamber 3, the top wall, and front wall of which 30 is provided with a keyhole shaped opening 4 and a vertical opening 5 respectively for a purpose hereinafter mentioned. The lower end of the casing has a bore 5' concentric with, but of larger diameter than 35 the chamber 3, and the end of the casing opposite the enlargement has a bore or socket 6 for rotatably and slidably retaining one end of a U-shaped shackle 7, the other end of which is provided with a plurality of 40 notches 8.

9 is a spindle longitudinally grooved as at 10 having a plurality of spaced disks 11 secured thereto by means of pins 12. If desired these disks may be formed integral 45 with spindle.

A plurality of rotatable tumblers or disks 13 are arranged on the spindle alternately with respect to the fixed disks 11. The disks 11 and tumblers 13 are of the same diameter 50 and each is provided with a recess 14, the recesses in the disks 11 being in vertical alinement when the parts of the lock are assembled. The disks 11 and tumblers 13 fit snugly within the tumbler chamber 3, but 55 not so tightly as to prevent the tumblers from being rotated. The spindle and tum-

blers are locked within the casing by means of a large disk 14' on the lower end of the spindle fitting within the bore 5', and secured to the casing by any suitable means 60 such as rivets 15. The upper and lower ends of the spindle are flush with the upper and lower ends of the casing with the exception of the projection 16 on the lower end of the spindle and it will be noted that the 65 rectangular portion of the opening 4 in the casing communicates with the groove 10 of the spindle. This projection 16 extends through a central opening in the large disk 14' and is adapted to be grasped by a pair 70 of pliers or the like to facilitate the withdrawal of the spindle and disks when necessary.

To facilitate the manual rotation of the tumblers the edges of the casing adjacent 75 the vertical opening 5, are beveled and the periphery of the tumblers are milled.

To lock the lock it is simply necessary to first manipulate the tumblers until the recesses therein are in vertical alinement with 80 the recesses in the disks 11, then insert the notched end of the shackle through opening 4, down the groove in the spindle and through the recesses in tumblers and disks. After the shackle has been pushed well 85 home, one or more of the tumblers is rotated, thus securely locking the shackle against withdrawal.

For convenience in operating the lock, the disks 11 are numbered consecutively from 1 90 to 4, the numbers being arranged in vertical alinement, and the tumblers each have one or more letters arranged about their periphery. To bring the recesses in the tumblers in alinement with the recesses in the disks 11, 95 a predetermined combination of letters are brought into vertical alinement with each other and with the numbers on the disks. For the sake of illustration, the combination of letters to be brought into register with 100 the vertical opening 5 is I D A S.

It will be seen from the foregoing that I have devised a lock which owing to its simplicity of structure will be cheap to manufacture and not liable to get out of order. 105

Having thus described my invention what I claim is:

A lock comprising a body portion having a cylindrical enlargement at one side bored to form a tubular chamber having a lower 110 open end and a reduced opening in the upper end of the body portion communicating

with the bore, the other side of the body portion provided with a vertical socket, a grooved spindle within the tubular chamber and having a reduced upper end passing through the reduced opening in the upper end of the body portion, a plurality of spaced members fixed to the spindle and snugly fitting the tubular chamber and provided with recesses, rotary members interposed between the said fixed members and having recesses adapted to register with the recesses in the fixed members, a disk closing the lower end of the tubular chamber and

having a central opening, a pin carried by the spindle passing through said opening, 15 and a shackle having one end rotatably and slidably secured within the socket and the other end of said shackle being notched and entering the groove in the spindle and to fit said recesses.

In testimony whereof I affix my signature in presence of two witnesses.

ROBERT DRUMMOND.
